US00D360903S

United States Patent [19]

Barr et al.

[11] Patent Number: Des. 360,903

[45] Date of Patent: ** Aug. 1, 1995

[54] **CONTROLLER FOR A VIDEO GAME MACHINE**

[75] Inventors: **Lance Barr**, Redmond, Wash.; **Kenichiro Ashida**, Kyoto, Japan

[73] Assignee: **Nintendo Company, Ltd.**, Japan

[**] Term: **14 Years**

[21] Appl. No.: **15,819**

[22] Filed: **Nov. 30, 1993**

[30] **Foreign Application Priority Data**

Jun. 28, 1993 [JP] Japan 5-19903

[52] U.S. Cl. **D21/48**
